(57) **CLAIM**

The ornamental design for a dishwasher panel, as shown and described.

DESCRIPTION

FIG. 1 is a front view of a dishwasher panel showing a first embodiment of our new design;

FIG. 2 is a perspective view thereof;

FIG. 3 is a front view of a dishwasher panel showing a second embodiment of our new design;

FIG. 4 is a perspective view thereof;

FIG. 5 is a front view of a dishwasher panel showing a third embodiment of our new design;

FIG. 6 is a perspective view thereof;

FIG. 7 is a perspective view of a dishwasher panel showing a fourth embodiment of our new design;

FIG. 8 is a front view thereof;

FIG. 9 is a top view thereof; and,

FIG. 10 is a right side view thereof.

The rear and bottom views of the dishwasher panels are not shown and do not form a part of the claimed design.
